UNITED STATES PATENT OFFICE.

SAMUEL B. MORRELL, OF GLOVERSVILLE, NEW YORK.

GAUNTLET-GLOVE.

1,276,099.

Specification of Letters Patent. Patented Aug. 20, 1918.

Application filed November 13, 1917. Serial No. 201,804.

To all whom it may concern:

Be it known that I, SAMUEL B. MORRELL, a citizen of the United States, residing at Gloversville, in the county of Fulton and 5 State of New York, have invented a new and useful Gauntlet-Glove, of which the following is a specification.

This invention has reference to gloves, and more particularly to gloves of the gauntlet 10 type. The object of the invention is to provide a gauntlet construction which will open widely to admit the corresponding portion of the garment of the wearer and which may be closed so effectively as to exclude wind, 15 dirt, etc., without the necessity of providing a gore or gusset.

The gauntlet cuff has loose or open ends arranged to pass easily one over the other, and these ends are so constructed that they 20 will not buckle or bulge, while the ends and corners of the cuff tend to constantly maintain their original shape.

Closing devices are provided on the cuff that may be easily grasped, particularly 25 when the wearer has one glove on or the glove is bulky about the fingers, because of lining, and the compass of the cuff is readily reduced so that one end of the cuff will overlie and firmly engage against the other. 30 Furthermore, the arrangement is such that the presence of edges or like parts that might come in contact with or catch upon structures present in automobiles or flying machines, etc., are reduced to a minimum, and 35 the disadvantages which occur in gloves having the gauntlet cuff made with gores or other like closing devices are effectively eliminated.

The invention will be best understood 40 from a consideration of the following detailed description, taken in connection with the accompanying drawings forming part of this specification, with the further understanding that, while the drawings show a 45 practical form of the invention, the latter is not confined to any strict conformity with the showing of the drawings but may be changed and modified so long as such

changes and modifications come within the scope of the appended claims. 50

In the drawings:

Figure 1 is a perspective view of a glove embodying the invention, showing the gauntlet cuff in the open position;

Fig. 2 is a perspective view of the gauntlet 55 and wrist portion of the glove in the closed position;

Fig. 3 is a displayed view of the gauntlet cuff separate from the body of the glove;

Fig. 4 is a perspective view of a portion of 60 the gauntlet part of the glove along the little finger line;

Fig. 5 is a view similar to Fig. 2, but illustrating some details not shown in Fig. 2.

Referring to the drawings, there is shown 65 a glove 1 having a hand portion 2, wrist portion 3 and gauntlet or cuff portion 4. The wrist portion is provided with a take up strap 4^a which, however, forms no part 70 of the invention and has been long in use 75 and therefore requires no special description. The cuff or gauntlet 4 is shown separately in Fig. 3, laid out or displayed. The cuff has two end portions 5 and 6, with the portion 5 wider and longer than the portion 6, and these portions are reinforced to make them stiffer than the main portion of the cuff. At intervals, the cuff is provided with 80 ribs 7 which also serve to strengthen and stiffen the cuff. Each end portion 5 and 6 has rounded extremities 8 which, in the completed glove, prevent any relatively sharp corners which might contribute to the catching of the gauntlet upon extraneous articles. 85

The two end portions of the cuff are not fastened together by a gore or gusset as is the customary practice in gauntlet gloves, but are freely separated (see Fig. 4). Where the end portions 5 and 6 join the wrist portion of the glove, there is provided in the wrist portion a notch 9 merging into the little finger seam 9^a, and at this point there is also provided a tab 10 made fast to the material of the glove, reinforcing the latter 95 adjacent to the small end of the notch 9.

Fast to the end portion 5 on the exterior thereof and immediately adjacent to the wrist of the glove is one end of a strap 11, while on the gauntlet portion of the glove 5 closely adjacent to the wrist are fastening devices 12, the strap 11 carrying a socket member 13 capable of snapping over either one of the fastening devices 12. There are usually provided two spaced fastening devices 12 to permit more or less adjustment, but a greater or less number of such devices 10 may be employed.

Fast to the smaller end portion 6 of the cuff of the glove is one end of a strap 14, while at a similar point in the end portion 15 5 of the glove is a slot or opening 15 having a tab 16 immediately adjacent thereto and carrying a link 17 on which is mounted a roller 18. The strap 14 is threaded through 20 the link 17 and carries a snap member 19 arranged to engage either one of fasteners 20, there being two such fasteners shown in the drawings located on the cuff 4 near the end thereof remote from the fasteners 12. 25 It will be understood, however, that one fastener or more than two fasteners may be employed, the purpose of more than one fastener being to allow for adjustment.

The cuff, because of the absence of any 30 gore or gusset may be opened widely, admitting the corresponding portion of the garment of the wearer. Then the end portion 5 of the cuff readily falls over the end portion 6, which latter is housed under the 35 wider portion 5, with said wider portion 5 lying snug and flat against the end portion 6 and onto the body of the cuff adjacent to it. This causes the folding of the wrist portion 40 of the glove at the other side of the notch 9, thus effectively closing the portion of the gauntlet where the two parts 5 and 6 overlap. The strap 11 may be readily fastened in place, thus closing the wrist portion 45 of the glove and corresponding portion of the gauntlet against the possibility of admission of dirt or wind or water. The strap 14 can readily be drawn over the portion 5 of the cuff, and secured to one or the other of the fasteners 20, thus effectively closing 50 the corresponding portion of the glove against weather effects. The parts come together flat and close, and there are no corners or the like to catch upon projections or parts of mechanisms.

Moreover, the straps 11 and 14 so engage 55 the cuff of the glove that the loose ends will pass easily over each other and lie close, and such ends and the corners of the cuff will maintain their original shape much longer 60 than heretofore.

The fastening arrangement has the advantage of not only holding the cuff closely about the corresponding portion of the gar-

ment of the wearer, but is capable of being 65 easily grasped for manipulation, even when the glove is lined and thereby increased in bulk in the finger portions. By passing the strap 14 through the slot 15, it not only serves to hold the corresponding end of the 70 gauntlet cuff closed, but serves to flatten the portion 5 against the portion 6 and onto the adjacent part of the gauntlet toward the fasteners 20.

While the snap type of fastener has been 75 shown and answers the purpose, it is to be understood that other forms of fasteners may be employed, and that in place of the straps used to hold the gauntlet closed, other means may be employed for the purpose.

What is claimed is:

1. A gauntlet glove having a cuff with separated ends having reinforced parts extending crosswise of the length of the cuff, one reinforced end being wider and longer than the other and arranged to overlap the 85 second-named end portion when the cuff is closed, and fastening means on the cuff for holding the longer and wider end in overlapping relation to the narrower and shorter end, the fastening means at the wrist end of 90 the cuff having coacting elements, one fast to the wider end and the other fast to the cuff adjacent to the narrower end thereof, and the other fastening means being fast to the narrower end of the cuff and threaded 95 through the wider end thereof.

2: A gauntlet glove having a cuff portion fast to the wrist part of the glove, with said wrist part provided with an expanding notch on the little finger line, and the cuff portion having terminal parts wholly separated, and coacting fastening means on the cuff portion of the glove, both ends of the cuff being reinforced or stiffened and one end being longer and wider than the other 105 end to be folded thereover in close contact therewith by the fastening means.

3. A gauntlet glove having a cuff portion with freely separated ends, one of the ends having a strap fast at one end thereto, and fastening means for the strap adjacent to said end, and the other end portion of the cuff having a slot therethrough, and a tab fast to the cuff adjacent to the slot and provided with a loop matching the slot and 115 through which the strap is threaded, whereby the two ends of the cuff may be drawn together by the strap without strain upon the portion of the glove pierced by the slot.

4. A gauntlet glove having a cuff portion with freely separated ends, one of the ends having a strap fast at one end thereto, and fastening means for the strap adjacent to said end, and the other end portion of the cuff having a slot therethrough, and a tab 120 fast to the cuff adjacent to the slot and pro-

vided with a loop matching the slot and through which the strap is threaded, whereby the two ends of the cuff may be drawn together by the strap without strain upon the portion of the glove pierced by the slot, said loop being provided with a roller where engaged by the strap to facilitate the movement of the strap through the loop.

Copies of this patent may be obtained for five cents each, by addressing the "Commissioner of Patents, Washington, D. C."

In testimony, that I claim the foregoing as my own, I have hereto affixed my signature in the presence of two witnesses.

SAMUEL B. MORRELL.
